COVERED HOT FOOD TRAY

Steve Cyr and Mark Whelan, Chippewa Falls, Wis.,
assignors to Standard Oil Company, Chicago, Ill.

Filed Jan. 29, 1971, Ser. No. 111,166

Term of patent 14 years

Int. Cl. D9—03

U.S. Cl. D9—185

*Fig. 3Fig. 4Fig. 5*FIG. 1 is an interior view of a covered hot food tray showing our new design in its open position;

FIG. 2 is a bottom plan view thereof;

FIG. 3 is a reduced scale front elevational view in a closed position;

FIG. 4 is a side elevational view thereof, the opposite side being a mirror image of the side shown; and

FIG. 5 is a rear elevational view in the closed position.

We claim:

The ornamental design for a covered hot food tray, as shown and described.
